UNITED STATES PATENT OFFICE.

DAVID J. WEIGEL, OF PLATTEVILLE, WISCONSIN.

TIE.

1,090,768.

Specification of Letters Patent.

Patented Mar. 17, 1914.

Application filed September 19, 1913. Serial No. 790,707.

To all whom it may concern:

Be it known that I, DAVID J. WEIGEL, a citizen of the United States, residing at Platteville, in the county of Grant and State 5 of Wisconsin, have invented new and useful Improvements in Ties, of which the following is a specification.

The present invention relates to improvements in ties for railway rails, the object 10 being to simplify and improve the present construction of metallic ties by producing a tie made up of companion sections having integrally formed thereon rail-engaging lips, which may be easily and quickly connected 15 together, or separated as occasion demands, and each of which is provided with a partially open side whereby a proper amount of ballast may be inserted within the tie to cause the same to be firmly seated within the 20 roadbed and retained against lateral, or transverse movement.

With the above recited objects in view and others which will appear as the nature of the invention is more fully understood, the 25 improvement resides in the construction, combination and arrangement of parts set forth in the following specification and falling within the scope of the appended claims.

In the drawings: Figure 1 is a perspective view of a tie constructed in accordance with the present invention, the rails being positioned thereon. Fig. 2 is a similar view illustrating the employment of fish plates in connection with the rail engaging lips 35 formed with the tie, whereby two rails may be connected and secured upon the tie, Fig. 3 is a view illustrating the manner in which the two sections comprising the rail are brought into engagement with the rail and 40 with each other, Fig. 4 is a detail perspective view of one of the tie sections, Fig. 5 is a central transverse sectional view through the tie, Fig. 6 is a detail horizontal sectional view taken through one end of the tie, Fig. 45 7 is a detail perspective view illustrating one form of a rail clamp which may be secured upon the tie, Fig. 8 is a similar sectional view illustrating a rail secured to the tie by another form of clamp, and Fig. 9 is 50 a perspective view of a still further modified form of rail engaging clips or clamps.

The tie T comprises two companion sections each of a similar construction, and which are designated by the numerals 1 and 55 2 respectively. Each of the sections includes an inner vertically straight wall 3, a

top and a bottom wall 4 and 5 respectively, the said walls 4 and 5 being in the nature of flanges which project outwardly at a right angle from the vertical wall 3. The sections, 60 at one of their ends, are provided with depressed or stepped portions in the upper and lower walls, which are designated by the numerals 6 and 7, respectively, being horizontally straight and in a plane parallel 65 with but spaced from the upper and lower walls 4 and 5. The shoulders or walls provided between the horizontally straight portions 6 and 7 and the top and bottom portions 4 and 5 of each of the ties are arranged 70 each at an angle from its inner wall 3 to its outer corner, the said angular walls or shoulders being designated by the numerals 8 and 9 respectively. The tie sections are also provided with ends 10 and 11, the end 75 10 being provided at the stepped portion of each of the sections, and the said end is formed with an opening 12, the purpose of 80 which will hereafter be set forth. Each of the sections is formed at its inner edge, and upon its top 4 with rail-engaging hooks 13 and 14, both of the hooks having their engaging fingers pointed in the direction of the ends 10, and the top 4 of the said sections is formed with bolt openings 15, the 85 said openings being arranged in pairs, one close to each of the hooks 13 and the second spaced a suitable distance away from the hook 14. The end 11 extends a suitable distance beyond the inner walls 3 of each of 90 the sections, and the top and bottom walls are also projected angularly from their connection with the wall 3 to the outer edge of the extending end 11. By this arrangement the end 11 forms a compartment 17, the 95 edges of the wall 16 agreeing with the beveled or inclined shoulders 8 and 9 of the co-acting section, so that the inner faces of the said portions 16 rest upon the walls 6 and 7, thus enveloping the end 10 of the said co-acting section within the compartment 17 of the first section, and when the sections are thus assembled, both the upper and lower faces of the sections are retained horizontally straight. The extending portion of 100 the end 11 is formed with a bolt opening 18, and when one of the sections is slid longitudinally of the other section, after a rail R has been positioned upon one of the said sections, the hooks 13 and 14 will engage 110 with the base flanges of the rails, and bolts 19 are passed through the registering open-

ings 12 and 18, while nuts 20 are employed for sustaining the bolts upon sections and the sections in locked position.

From the above description, it will be noted that the tie is substantially I-shaped in cross section, and the opposite open sides of the tie are adapted to receive the ballast from the roadbed, which, when properly tamped and the tie embedded within the roadbed, danger of the lateral or longitudinal movement is effectively prevented.

In order to assist the hooks 13 and 14 in retaining the rails R upon the tie, angular clamps 21 may be employed, said clamps having rail engaging faces and the angular portions of the same may be centrally reinforced through the medium of integrally formed ribs 22. The lower angular portion of the clamps which is stepped to rest upon the upper face of the tie is formed with an elongated opening 23 through which the hooks 13 project, and the base of the said flange is provided with openings 24 which are adapted to receive bolts 25 that project through the openings 15 in the tie, the said bolts being provided with securing nuts 26.

When two rails are to be secured upon the ties, an angular fish plate 27 is employed, the said plate being substantially similar to the clamp 21, but of course, being of a greater length. The fish plate has its stepped horizontal or base portion provided with an elongated opening 28 through which the hooks 13 or 14 extend, and the vertical member of the fish plate 27 is formed with a plurality of openings 28 for the reception of bolts which also pass through registering openings in the webs of the rails. The plates 27 may be employed upon the opposite faces of the rails, and the bolts are provided with the usual securing nuts.

In some instances it has been found desirable to reinforce the hooks 13 and 14, or to provide a substitute therefor should the said hooks become broken, and to accomplish this, clips 28' may be employed, the said clips comprising angle members which have their base portions provided with openings which are adapted to register with the openings 15, and the said clips 28' are secured through the medium of bolts 29 passing through the openings and nuts 30 for the said bolts.

In lieu of the clips above mentioned, I have found it desirable to employ a fastener or clip of a somewhat different construction, the said clip being designated by the numeral 31, and is constructed of a single piece of metal to include a rail base flange

engaging lip 32 and a base portion 33. The base 33 has one of its longitudinal edges bent to provide a substantially U-shaped flange which underlies the base, and which is adapted to engage with one of the longitudinal edges upon the upper flanged portions 4 of each of the rail sections, the body being further provided with an opening 34 which is adapted to register with any of the openings 15, and the bolts 29 and their nuts 30 are employed for securing the member 31 upon the sections of the tie.

From the above description taken in connection with the accompanying drawings, the simplicity of the device as well as the advantages will it is thought, be perfectly apparent to those skilled in the art to which such inventions appertain without further detailed description.

Having thus described the invention, what I claim is:

1. A tie comprising companion shaped members which, when assembled, are I-shaped in cross section, the sections having ends, one of the ends of each of the sections having its top and bottom wall stepped, the opposite end of each of the sections having its top and bottom wall and its end extended, the top and bottom extensions engaging with the stepped ends of the co-acting tie sections and the extended end of one of the tie sections overlapping the end of the adjacent tie section, and means arranged between the ends for securing the tie sections.

2. A rail tie comprising two companion shaped sections which, when assembled are I-shaped in cross section, the meeting walls of the sections being provided with integrally formed rail engaging hooks, the opposite ends of each of the ties being depressed upon their upper and lower surfaces and having an angular shoulder connecting the said faces with the depressions, the opposite ends of the tie sections being extended beyond their inner faces, and the top and bottom walls extended angularly and connected with the ends, the said angular portions adapted to abut with the angular shoulders provided by the depression, the ends being formed with registering openings, bolts passing through the openings and nuts for the bolts.

In testimony whereof I affix my signature in presence of two witnesses.

DAVID J. WEIGEL.
